UNITED STATES PATENT OFFICE

162,014

BONNET OR THE LIKE

Marguerite Deslauriers, Montreal, Quebec,
CanadaApplication January 22, 1949, Serial No. 411
In Canada October 28, 1948

Term of patent 7 years

(Cl. D3—13)

To all whom it may concern:

Be it known that I, Marguerite Deslauriers, a citizen of Canada, residing at city of Montreal, Province of Quebec, Canada, have invented a new, original, and ornamental Design for a Bonnet or the like, of which the following is a specification, reference being had to the accompanying drawing, forming part thereof. In the drawings,

Fig. 1 is a side view of a bonnet, showing my new design;

Fig. 2 is a rear view; and

Fig. 3 is a side perspective view thereof.

I claim:

The ornamental design for a bonnet or the like, as shown.

MARGUERITE DESLAURIERS.
